TUBE BEADING AND FLARING TOOL

Howard F. Brinen, Racine, Wis., assignor to
 Young Radiator Company, Racine, Wis., a corporation of Wisconsin

Application March 31, 1948, Serial No. 18,192

2 Claims. (Cl. 153—80)

1

The main objects of this invention are, to provide an improved tool for beading and flaring the ends of metal tubes into a header plate; to provide a tool of this type having an improved arrangement of a beading die and a flaring die whereby the flaring of the tube end is effected by a movement of the flaring die axially of the beading die following its expansion to form the bead; to provide improved means for effecting the operation of said dies; to provide an improved construction and arrangement of resilient means for normally retracting the die-operating means; and to provide an improved tool of this type which is inexpensive to manufacture and easy and positive in its operation.

In the accompanying drawings,

Fig. 1 is a side view of a preferred form of beading and flaring tool constructed in accordance with this invention, the parts being shown in relatively retracted positions and with the beading and flaring dies positioned with respect to a tube end which is to be anchored in a header plate;

Fig. 2 is an enlarged longitudinal section of the tool showing the position of the parts thereof and the condition of the tube subsequent to the beading operation;

Fig. 3 is a similar view showing the position of the tool parts and the condition of the tube subsequent to the flaring operation;

Fig. 4 is an enlarged section taken on the line 4—4 of Fig. 1; and

Fig. 5 is a perspective view of the spindle collar whereon the operating handles are pivotally supported.

An improved tube-beading and -flaring tool constructed in accordance with this invention comprises a housing 6, mounting a tube-flaring die 7, wherein is slidably supported a telescopically-arranged tubular member 8, mounting a tube-beading die 9, and a spindle 10, mounting a mandrel 11, the relative axial movements of which housing, member, and spindle are effected by a pair of handles 12 acting against the normal retractive force of springs 13 and 14.

The housing 6 comprises forward and rear parts. The forward part is of tubular form providing a chamber and a bore wherein is slidably supported the tube-beading die chamber 8. The outer end of this tubular forward housing part is tapered to provide a tube-flaring die 7. The rear part of the housing 6 comprises rearwardly extending rods 20 spanned at their outer ends by a cross bar 21 and anchored to a cross head 18 integral with the forward tubular housing part

2

and by means of which the housing chamber closure 19 is held in place.

The closure 19 is held in place by the rods 20 which have their inner ends threaded into the cross-head 18 as shown at 22 and provide shoulders 23 which hold the closure 19 against the cross-head 18. The closure 19, in its rear face, is provided with recesses 24 which serve to engage and retain in proper position the cam ends of the operating handles 12.

The cross-bar 21 is held in place on the rods 20 against the action of the spring 14 by the spring rings 25 seated in annular recesses formed in the ends of the rods 20.

15 As herein shown, the tube-end flaring-die 7 is a tapered surface formed on the end of a nipple 27 threaded onto the end of the housing 6 and opposed to the tube-beading die 9. If preferred, the tapered surface 7 could be formed integral with the end of the housing 6. As will be pointed out more fully hereinafter, the flaring die 7 coacts with the beading die 9 to flare the end of the tube T into the header plate H.

The die member 8 is of tubular form and is 25 slidably mounted in the bore 17 with its opposite ends extending into the housing chamber 16 and beyond the flaring die 7. At its inner end the member 8 is formed with a head 28 slidable in the housing chamber 16. The die 9, located 30 at the outer end of the member 8, comprises an annular enlargement 29 and a plurality of slits extending inwardly from and through the annular enlargement 29 to provide a plurality of fingers 30 which are normally biased toward each 35 other by the resiliency of the tubular member 10. Thus the outside diameter of the annular enlargement 29 normally is less than the inside diameter of the tube T which the tool is to be used to expand. This permits the enlargement 40 to slip into the end of the tube T preparatory to beading it into a header plate H and flaring the outer end of said tube after the beading operation.

The spindle 10 is slidably sheathed in the 45 tubular member 8. Its opposite ends extend beyond the housing cross-head 21 and the annular enlargement 29 on the member 8. The rearwardly-extending part provides a pivotal support for the handles 12 as will appear more fully hereinafter. At its forward end the spindle 10 is enlarged to provide the mandrel 11.

The mandrel 11 provides a tapered surface 31 which is received into the split end of the member 8, when the spindle is drawn rearwardly, and 55 causes an expansion of the annular enlargement

29 to form a bead in the tube T inwardly of the header plate H. A shoulder 32, formed on the mandrel at the outer extremity of the taper 31, abuts the tubular member 8 and limits the axial movement of the spindle 10 relative to the member 8, and consequently the expansion of the enlargement 29.

The operating handles 12 are in the form of a pair of curved elements crossed and pivotally supported on a collar 33 adjustably mounted on the spindle 10. The forward extremities of the handles are received in the slots 24 cut in the closure 19 and, when the outer ends of the handles 12 are compressed, have a camming action on the housing 6 to effect the required relative movement of the spindle 10, the member 8, and the housing 6.

The collar 33 is provided with trunnions 34 on which the handles are held by spring rings 35. Set screws 36 serve to fix the position of the collar 33 on the spindle 10 and thus permit the pivot of the handles 12 to be adjusted axially of the spindle 10 and consequently affect somewhat the stroke of the spindle 10.

The springs 13 and 14 cooperate to normally shift the housing 6, member 8, and spindle 10 relative to each other to retract the mandrel from the beading die 9 and space the latter with respect to the flaring die 7.

The spring 13 embraces the spindle 10 within the chamber 16 between the head 28 on the member 8 and the housing closure 19. It thus presses the head 28 against a shoulder 37 formed at the juncture of the chamber 16 and bore 17. Thus the annular enlargement 31 of the beading die 9 is held in its fully extended position beyond the end of the housing 6 and accordingly appropriately spaced from the tube-flaring die 7 of said housing.

The spring 14 embraces the spindle between the collar 33 and the cross-bar 21 and normally shifts the mandrel toward its fully-retracted position with respect to the annular enlargement 29 of the beading die 9.

A spring 15 spans the handles 12 rearwardly of the housing cross-head 21 and tends to limit the separation of the outer ends of the handles, as influenced by the springs 13 and 14, so as to retain the handles in their expanded relationship, within the grasp of the operator's hand.

The operation of this improved tube-beading and -flaring tool is as follows:

The mandrel 11 and beading die 9 being shifted by springs 13 and 14 into their fully extended positions relative to each other and to the flaring die 7, the tool is ready to be inserted into the end of a tube T. Preferably it is placed so that the tapered end of the bushing 27 abuts against the end of the tube T. That so locates the beading die 9 in the tube T that the bead will be formed directly inwardly of the header plate H. (See Fig. 1.)

With the tool so positioned the compression of the handles 12 causes the camming action thereof against the housing closure 19 to draw the spindle 10 rearwardly. The tapered part 31 enters the outer end of the member 8, expanding the annular enlargement 29 and forming a bead in the tube T directly inward of the header plate H, as indicated in Fig. 2. The contact of the mandrel shoulder 32 with the end of the member 8 limits any further relative movement of the spindle and member 8. The expansion of the enlargement 29 into the tube precludes any movement of the member 8 relative to the hous-

ing 10. However, the handles 12 are subject to further compression. This continues to exert a pressure between the spindle 10 and the housing 6. Consequently the housing moves forwardly on the member 8 against the action of the spring 13. This presses the die 7 into the tube end, causing a flaring thereof, as indicated in Fig. 3.

Upon completing the formation of the bead and the flare a release of the handles 12 permits the springs 13 and 14 to act to restore the housing 6, member 8, and spindle 10 to their normally-extended positions, as shown in Fig. 1.

Other variations and modifications in the details of structure and arrangement of the parts may be resorted to within the spirit and coverage of the appended claims.

I claim:

1. In a tool of the class described the combination of a housing having forward and rear parts, the former of which is chambered and has a bore extending from the chamber through the forward portion of said housing and forming a shoulder at the juncture of said chamber and bore, a tubular member slidably mounted in said bore and having its opposite ends respectively terminating within said housing chamber and extending beyond the forward end of said housing, said member having a head formed on the chamber end thereof and an annular enlargement formed on the outer end and having slits extending inwardly from the outer end thereof through said enlargement to provide fingers normally biased toward each other by the resilience of said member whereby the normal outside diameter of said annular enlargement is less than the inside diameter of a tube which said tool is to be used to expand, a spindle slidably sheathed in said member and having the opposite ends respectively extending beyond the forward end of said member and rearwardly of the chambered forward part of said housing, a mandrel formed on the forward end of said spindle and adapted to be drawn into the split end of said member to effect the expansion of said annular enlargement, a pair of operating handles pivotally connected to the rearward end of said spindle with the forward ends of said handles camming against said housing to effect an axial movement of said spindle and member relative to each other and to said housing when the outer ends of said handles are compressed, a closure for said housing chamber, a compression spring interposed between said member head and said closure whereby said head is normally urged against said housing shoulder to position said member enlargement with respect to the outer end of said housing, and a second compression spring interposed between said rear housing part and said spindle to normally shift said spindle to retract said mandrel from said member enlargement.

2. In a tool of the class described the combination of a housing having forward and rear parts, the former of which is chambered and has a bore extending from the chamber through the forward portion of said housing and forming a shoulder at the juncture of said chamber and bore, a tubular member slidably mounted in said bore and having its opposite ends respectively terminating within said housing chamber and extending beyond the forward end of said housing, said member having a head formed on the chamber end thereof and an annular enlargement formed on the outer end and having slits extending inwardly from the outer end thereof

through said enlargement to provide fingers normally biased toward each other by the resilience of said member whereby the normal outside diameter of said annular enlargement is less than the inside diameter of a tube which said tool is to be used to expand, a spindle slidably sheathed in said member and having the opposite ends respectively extending beyond the forward end of said member and rearwardly of the spindle of said housing, a mandrel formed on the forward end of said spindle and adapted to be drawn into the split end of said member to effect the expansion of said annular enlargement, a trunnioned collar slidably mounted on said rod rearwardly of said forward housing part, means for fixing said collar on said spindle, a pair of operating handles pivoted one to each of said collar trunnions with the forward ends of said handles camming against said housing to effect the axial movement of said spindle and member relative to each other and to said housing when the outer ends of said handles are compressed, a closure for said housing chamber, a compression spring interposed between said member head and said closure whereby said head is normally urged

5

10

15

20
